Primary Examiner — Janice Hallmark(74) *Attorney, Agent, or Firm* — Ware, Fressola, Maguire & Barber LLP(57) **CLAIM**

We claim the ornamental design for a tower fan, as shown and described.

DESCRIPTION

FIG. 1 is a front view of a tower fan showing our new design;

FIG. 2 is a front perspective view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines in the drawings depict parts of the tower fan that form no part of the claimed design.

1 Claim, 6 Drawing Sheets(56)
